BUILDING BLOCK AND WALL
CONSTRUCTION

Frederick T. Heath, Syracuse, N. Y.

Application November 18, 1932, Serial No. 643,197

8 Claims. (Cl. 72—41)

My invention is directed to improvements in load-bearing wall constructions for buildings and has for its general object the provision of a simplified form of combined tile and brick construction for a wall, and particularly building walls of the type wherein a brick front or facing is bonded into the wall structure and the wall construction is completed by the use of so-called "back-up tile".

10 A further object of my invention is the provision of a building block which will be quite simple in cross-sectional form and adaptable to ready manufacture and of an external shape and size to facilitate the laying of the blocks in the 15 wall structure by the building mechanic.

A still further object of my invention is the provision of a building block, which, while being of a shape to facilitate its economical manufacture, its handling and its laying, will have the 20 physical characteristics required of a load-bearing tile and which block may be suitable for the partitioning thereof, whereby a standard unit block may also serve at the place of wall construction as a header tile, a full unit tile or 25 a half tile, as desired.

Other objects of my invention will hereinafter become apparent from a description of the drawing, which illustrates a building block unit and 30 three adaptations of the block to load-bearing tile and brick wall structures of varying thicknesses.

In the drawing, Fig. 1 is a perspective view of my unit block; Fig. 2 is a cross-section of a twelve-inch wall structure embodying the use of 35 the block; Fig. 3 is a cross-section of a sixteen-inch wall; Fig. 4 is a cross-section of an alternate form of sixteen-inch wall construction; Fig. 1a is a perspective view of a header block obtained by 40 parting the unit block shown in Fig. 1, and Fig. 1b is a perspective of a half block obtained from the unit block shown in Fig. 1.

My invention contemplates the provision of a building block of the hollow load-bearing tile type, provided with an arrangement of internal 45 web and outer shell proportioning which will permit the block to be divisible into half-block or header blocks by the mason, by requiring only the splitting of one internal web and one external wall of the block, and I prefer to incorporate 50 this arrangement in a hollow load-bearing tile, preferably substantially square in cross-section, and with a side or top dimension of the block equal to the height of three bricks plus two mortar joints. I arrange two parallel vertically extending webs and one horizontal web in such re-

lation to the cross-sectional center that by partitioning the block I may obtain a header block having a brick bonding inset substantially equal to the height of a brick plus a mortar joint, and I arrange the vertically extending parallel webs in 60 such manner as to retain substantially the full vertical load-bearing alignment of the header blocks and unit blocks when placed in the wall structure for maximum load strength and I also form the top bearing surface of the block where- 65 by a slot or groove extends longitudinally of the block to afford the ready partitioning referred to and to facilitate the handling of the block. The block is made preferably 7 $\frac{3}{4}$ " high and 8" wide, to prevent improper laying of the block on the 70 wall.

Such a block A is shown in Fig. 1 wherein the outer shell comprises the external side walls 8 and 9 and the bottom wall 10 of substantially the same thickness and dimension, and which may 75 be externally scored as desired for mortar-locking purposes. The top mortar-bearing surface comprises horizontally aligned top walls 11 and 12, the external walls 8, 9, 10, 11 and 12 forming in transverse cross-section substantially a square. Two internal webs 13 and 14 extend vertically 80 parallel throughout the height of the block, as shown, and are intersected by a horizontal or transversely extending web 16. The webs 13 and 14 are spaced apart a sufficient distance to afford the formation of an outwardly exposed void or slot 20 formed in the top of the block of such width, (preferably one inch) as to permit convenient gripping of the top of the block by the mason and for further convenient handling I 85 prefer to have slight overhanging portions 21 formed along the top edges of the slot 20 which may have the top longitudinal edges thereof slightly rounded to afford a comfortable grip to the mason.

To permit the unit block to be converted into a header block, the transverse web 16 is spaced downwardly from the top webs 11 and 12 a distance equal to substantially the vertical height of a mortar joint plus the vertical height of a 90 brick; whereby if the mason desires to obtain a header block he may do so by breaking the outer wall 8 and the internal vertical web 13 along planes defined by the dash lines 8a and 13a, respectively. A header block thus obtained is shown in Figs. 1a, 2 and 4, and is indicated by the reference numeral H. Should the mason desire to obtain a half-block for the purposes of building a thicker wall or for obtaining transverse bonding 95 of parallel courses of tile in thick walls, such as 100 105 110

is shown in Figs. 3 and 4, he may obtain the same by parting the unit tile A along planes indicated by dash lines shown at 13b and 14b, (Fig. 1). Kerfs k may be provided at the internal corners 5 where fractures may be desired.

The block is preferably made substantially square in cross-section with the longitudinal dimension equal to the side of the square,—that is, a cube form, and preferably of a seven and three-quarter inch dimension, whereby the height of the block will be equal to the height of three bricks, plus two intermediate mortar joints, and in a twelve-inch wall having a brick facing, the construction would be as shown in cross-section 10 in Fig. 2, wherein the unit blocks A would be laid in the wall in longitudinal bonding relationship,—that is, running bond relationship, with the header blocks H, the tile being set with the vertical webs 8, 9, 13 and 14 thereof in substantial load-bearing 15 relationship. In this construction, every sixth course of the longitudinal courses 28 of the brick facing would comprise a header course 30.

In Fig. 4 the sixteen-inch structure is shown, and courses of half-blocks K are run side by side 20 with full unit blocks A and header blocks H. The longitudinal arrangement of the respective courses is such as to obtain longitudinal bonding throughout the length of the wall. In Fig. 3 of the sixteen-inch wall construction, the header bonding 25 with the header course 30 is obtained by the use of an element M of the block and the units tile A are shown in staggered longitudinal courses to obtain the bond and the wall is completed by the use of half-blocks K. The blocks M are obtained by partitioning a half-block to remove the 30 upper portion thereof.

It will be noted that the half-blocks, header blocks and unit blocks all have a common top dimension, represented by the dimension G in Fig. 40 1, which affords a substantially uniform grip to the mason who is building the wall. This gripping distance is preferably made not greater than the width of a brick, thus greatly enhancing the dexterity which the mason can develop in handling the various shaped units, including the bricks 45 when building the wall.

The external shape of the unit block, while shown as substantially a cube, may be any desired length, such, for example, a twelve-inch length, 50 without loss of any of the advantages of my structure, with the exception that the units and half-units could not be stood up-ended to form end closure and pilaster constructions.

I claim:

55 1. A composite brick and tile wall, consisting of a facing of brick and a co-acting backing of hollow tile blocks laid with their voids extending horizontally, certain of said blocks having portions cut away and receiving inner portions of 60 said header brick in bonding relationship, and certain of said blocks having rectangular cross-section, the blocks with the cut-away portions having maximum cross-sectional dimensions equal to the corresponding maximum dimensions 65 of the cross-section of the other blocks, all of said blocks having a horizontally disposed cross-web spaced relative to the top shell of the block downwardly a distance substantially equal to the vertical dimensions of the brick plus a mortar joint, 70 some of which having that portion removed comprising a corner section thereof adjacent the facing of brick, to thereby form a bond with the header courses of the brick, and the other blocks being formed to have a centrally disposed exterior 75 exposed void between a pair of vertically disposed

webs whereby a convenient gripping of the tile may be afforded to the mechanic when the wall is being constructed.

2. A composite brick and tile wall, consisting of a facing of brick and a co-acting backing of hollow tile blocks laid with their voids extending horizontally, all of said blocks being of substantially equal corresponding overall cross-sectional dimensions, and having a horizontally disposed cross-web whose upper surface is spaced downwardly relative to the upper surface of the block a distance substantially equal to the thickness of a brick plus a mortar joint, some of which having that portion removed comprising an upper corner section thereof adjacent the facing of brick to thereby form a bond with the header courses of the brick and the other blocks being formed to have an exterior exposed void in its upper surface whereby a convenient gripping of the tile may be afforded to the mechanic when the wall is being constructed.

3. A composite brick and tile wall, consisting of a facing of brick and a co-acting backing of hollow tile blocks laid with their voids extending horizontally, all of said blocks being of substantially equal corresponding overall cross-sectional dimensions and having a horizontally disposed cross-web the outermost surface of which is spaced a distance substantially equal to the thickness of a brick plus a mortar joint from one of the exterior horizontal faces of the block, certain of said blocks being formed with an exterior exposed void in one of the horizontal faces of the block whereby the block may be divided into header blocks by splitting only one outer shell 105 and one internal web, and other blocks in bonded relationship having that portion removed comprising a corner section adjacent the facing of brick, the recess so formed receiving the inner portions of said header brick in bonded relation- 110 115 ship.

4. A hollow load bearing building tile adaptable for use in a wall constructed of tile having a brick facing and comprising a block substantially square in cross-section and having a horizontally 120 disposed internal web and a pair of vertically disposed internal webs, the vertical webs being arranged to be substantially equidistantly spaced relative to the center of the cross-section of the block, the top load-bearing surface of the block provided with an exteriorly disposed void formed by omission of that portion of the outer top load bearing wall of the block which would extend between said vertically disposed internal pair of webs, whereby the block may be conveniently grasped and manipulated by one hand 130 of the mason and whereby the block may be divided into header blocks or half blocks as desired by breaking only one outer wall and one internal web.

5. A hollow load bearing building tile adaptable for use in a wall constructed of tile having a brick facing and comprising a block substantially square in cross-section and having a horizontally disposed internal web and a pair of vertically 140 disposed internal webs, extending above and below the horizontal web, the vertical webs being arranged substantially equidistantly spaced relative to the center of the cross-section of the block, the top load bearing wall of the block being 145 slotted between the vertical webs, and the spacing of the horizontal web relative to said top wall being such that the block is divisible into header blocks and half blocks by fracturing only one outer wall and one internal web of the block. 150

6. A hollow load bearing building tile adaptable for use in a wall constructed of tile having a brick facing and comprising a block substantially square in cross-section and having a horizontally disposed internal web and a pair of vertically disposed internal webs, the vertical webs being arranged to be substantially equidistantly spaced relative to the center of the cross-section of the block, the space between the web being substantially equal to the mortar joint and the top load bearing surface of the block being provided with an exteriorly disposed void formed by omission of that portion of the outer top load bearing wall of the block which would extend between said vertically disposed internal pair of webs. 80
7. A hollow building tile adaptable for use in a wall constructed of tile having a facing of brick bonded to the tile backing with brick header courses and comprising a block substantially rectangular in cross-section and having a horizontally disposed internal web whose upper surface is spaced downwardly relative to the upper surface of the block a distance substantially equal to the thickness of a brick plus a mortar joint, and a pair of vertically disposed internal webs, 85
- the vertical webs being substantially equidistantly spaced relative to the center of the cross-section of the block, and the top surface of the block being provided with an exteriorly exposed void formed by an opening continuous from end to end of the block extending into the cell formed above the said horizontally disposed web and between the said pair of vertically disposed web. 90
8. A hollow building tile adaptable for use in a wall construction as a backing material for bonded brick facing and comprising a block substantially rectangular in cross-section, the vertical overall dimension of which corresponds to the dimension of any given number of brick courses less the thickness of one mortar joint, the top surface of the block being provided with an exteriorly disposed void formed by an opening continuous from end to end of the block, said void terminating at its lower extremity in an internal web extending horizontally from shell to shell, the void being of a depth from the upper surface of the block corresponding to one brick course. 95
